UNITED STATES PATENT OFFICE.

HARRY H. STOUT, OF NEW YORK, N. Y., ASSIGNOR TO GENERAL CHEMICAL COMPANY,
OF NEW YORK, N. Y., A CORPORATION OF NEW YORK.

ROASTING-FURNACE FOR SULFUR-BEARING ORES.

1,181,184.

Specification of Letters Patent.

Patented May 2, 1916.

Original application filed July 31, 1914, Serial No. 854,230. Divided and this application filed June 5, 1915.
Serial No. 32,251.

To all whom it may concern:

Be it known that I, HARRY H. STOUT, a citizen of the United States, and a resident of the borough of Manhattan, city, 5 county, and State of New York, have invented certain new and useful Improvements in Roasting-Furnaces for Sulfur-Bearing Ores, of which the following, taken in connection with the accompanying drawings, is

10 a specification.

My invention relates to the roasting of sulfur-bearing ores, especially in connection with a rotary roasting furnace of the type shown in United States Letters Patent, No. 15 976,175 to John B. F. Herreshoff, dated November 22, 1910, and the object of my invention is to provide a regulatable distribution of heat, and controllable temperature conditions on each of the several roasting 20 hearths or shelves of such a furnace and to provide a furnace structure capable of admitting of such controllable operation.

This application is a division of my application, Serial Number 854,230, filed July 25 31, 1914.

It has long been known that an obstacle to the most economical and efficient operation of furnaces of this type is the formation of incrustations which clog up the moving parts of the furnace, or of "scars", i. e. fused masses of the material undergoing roasting, which attach themselves with more or less firmness to the hearth surface or to the rabble teeth or to both, thus bringing 30 about inefficiencies in operation due to stoppage and due to the physical condition of the agglomerated material, which renders it incapable of being deprived of its sulfur content to the extent necessary for successful commercial operation. These scars or incrustations usually form in the upper hearth spaces the temperature of which is apt to be excessively high while the lower hearth spaces are at the same time at a temperature which is usually too low for efficient operation. If, as has been proposed, the furnace is operated at below normal capacity, the formation of these agglomerated masses may to some extent be prevented, 45 but such operation is obviously inefficient and is not capable of being controlled.

I have found that by a proper transfer of the heat generated on any hearth in excess of that heat necessary to bring about satis-

factory roasting, to some other hearth having insufficient heat or temperature conditions, satisfactory roasting can be effected, coupled with a capacity per day greater than under the most favorable conditions heretofore obtaining; that by so operating it is possible to have fewer interruptions than under the best practice heretofore obtaining, and fewer repair charges.

In order to make clear the nature of my invention and to explain fully the process thereof I will now refer to the accompanying drawings in which is shown a roasting furnace embodying my invention, in which drawings—

Figure 1 shows the furnace in central vertical section, and Fig. 2 shows a plan view thereof, certain parts being in section.

The furnace illustrated comprises a number of superposed hearths 1 extending inwardly from an outer, cylindrical wall 2 and 75 providing roasting spaces between the hearths, which spaces are traversed by rabble or stirring arms 3, rotatably supported by a central, vertical double-walled shaft 4. Through the central passage of the 80 shaft, air or other suitable cooling medium is forced, from which passage it passes through the several rabble arms in parallel and issues therefrom into the annular passage of the shaft, which surrounds the central passage thereof.

In communication with the top of the annular channel of the shaft is a transverse conduit 5, the ends of which connect with the bustle pipe 6, the latter being in the 90 form of a ring of approximately the same diameter as the furnace itself and being supported upon the cylindrical wall 2 of the furnace. The bustle pipe communicates with a plurality of vertical flues or conduits 95 7, preferably metallic, which are built into the wall 2, so that their inner walls are in direct contact with the products of roasting in the furnace hearth-spaces and which extend from the bustle pipe to the lowest 100 hearth-space. Air or other fluid is thus capable of being conducted by the conduits 7 from the bustle pipe to the roasting space of the said lowest hearth. It will be understood, of course, that the conduits may discharge into other hearth spaces than the lowest one and that certain of them may discharge into the lowest space while others

of them may discharge into other roasting spaces. I have found, however, that successful and efficient operation may be had in practice with a furnace in which all of 5 the conduits 7 discharge into the lowermost roasting space.

An outlet into the atmosphere is provided in the form of a stack 8 which may extend upwardly from the transverse conduit 5 and 10 is provided with a valve or damper *a*. A pipe 9 insulated from the heat of the furnace, or a plurality of such pipes, connects with the conduit 5 and extends downwardly; the lower end of said pipe is in 15 communication with the inlet conduit 10 which communicates at one end with the central passage of the shaft 4 and which is adapted to convey cooling air from a fan or other fluid-forcing apparatus (not shown) 20 into the shaft and, if desired, into the pipe 9, the latter preferably communicating with the conduit 10 at a point located between the fan and the shaft. A branch pipe 11 establishes communication between each pipe 9 25 and one or more of the roasting spaces, as for example, that of the lowermost hearth into which the flues or conduits 7 also discharge.

The transverse conduit 5 is provided with 30 dampers *b* located between the shaft 4 and the outlet 8 on the one hand and the bustle pipe 6 and the pipe 9 on the other hand. Dampers *c* are provided between the transverse conduit and the bustle pipe; dampers 35 *d* and *e* are provided in the pipes 9 respectively above and below the point of communication between said pipes and the branch pipes 11; and the branch pipes 11 are themselves provided with dampers *f*.

40 The device illustrated is adapted to be operated in a number of ways which will depend upon the nature and qualities of the ore being roasted, which ores may be, for example, iron pyrites, copper pyrites, pyrrhotite, blende, galena or various mixtures thereof. According to each method of operation, however, air, or other suitable cooling fluid, which has extracted a certain amount of heat from the furnace by being forced 45 through the rotary stirring system is passed into heat exchanging proximity to the hotter portions of the furnace and discharged into cooler portions thereof, so as to convey heat from said hotter portions to said cooler 50 portions and because of its pre-heated condition, to augment roasting in said cooler portions. In other words, the cooling air, after it has traversed the shaft and rabble arms of the rotary stirring system, is caused 55 to pass through the conduits 7 and to extract heat from the upper roasting spaces due to the fact that said conduits are made of material which conducts heat readily, said material being exposed to and in direct 60 contact with the atmosphere of said roasting 65

spaces; after being thus heated, the air is conducted, as shown, into the lowermost roasting space.

According to one method of operation, the dampers, *a*, *d*, and *f* are closed and the dampers *b* and *c* are open, the dampers *e* being either open or closed. Air is forced by the fan through the conduit 10 and passes therefrom into and through the rabble arm system from which it issues into the transverse conduit 5 and passes therefrom successively 70 into the bustle pipe 6 and heat exchanging conduits 7, finally discharging into the lower hearth space. If desired, the damper *a* may be opened slightly and if necessary the dampers *b* and *c* be closed slightly so as to cause any proportion of the air to pass from the transverse conduit into the atmosphere through the stack 8, and the remainder to pass through the conduits 7 into the lowermost combustion chamber. Further heat control may be had by opening the dampers *d* and *f* more or less and closing the damper *e*, the damper *a* being either open or closed, so that a portion of the air will pass down 80 through the pipe 9 into the branch 11 and discharge into the lower hearth space. 85

90 It is obvious that a suitable manipulation of the dampers will result in causing all of the air to pass into the atmosphere through the exit 8, all of it to pass through the heat interchanging conduits 7 into the lower portions of the furnace, all of it to pass through the external pipe 9 into said lower portions, all of it to pass through any two of these 95 passages 7, 8 and 9, or any proportion of it to pass through these two or three passages. It will be seen that the furnace is very flexible in its operation and can be accommodated to the roasting of any kind of ore. It 100 is further possible to manipulate the dampers in an obvious manner so as to cause all of the cooling air to pass from the rotary mechanism through the exit stack while at the same time air is caused to flow directly 105 from the conduit 10 into the pipe 9 and from said pipe either directly into the lower chamber in non-heated condition or through the heat exchanging conduits 7 into said chamber, the air in the latter case being pre-heated before passing into said chamber and serving to regulate and control the heat and 110 temperature of the furnace by extracting heat from the upper portions of the furnace, which heat has been conducted from the chamber through the metal forming the said conduits 7, and conveying such extracted heat into the lower portions of the furnace. 115

120 I claim:

125 1. In an ore roasting furnace having an outer, cylindrical wall a plurality of superposed roasting chambers and a rotary air-cooled rabble system, the combination of a metallic downwardly extending conduit the external surface of said conduit being 130

- exposed to the atmosphere of certain of said roasting chambers and the lower end thereof being in communication with the lowermost of said chambers, and means for conducting air from the upper end of the rabble system to the upper end of said conduit, substantially as and for the purpose described.
2. In an ore roasting furnace having an outer, cylindrical wall a plurality of superposed roasting chambers and a rotary air-cooled rabble system, the combination of a metallic, downwardly extending conduit the external surface of said conduit being exposed to the atmosphere of certain of said roasting chambers and the lower end thereof being in communication with the lowermost of said chambers, valved means for conducting air from the upper end of the rabble system to the upper end of said conduit, and valved means for conducting air from the upper end of the rabble system into the atmosphere, substantially as and for the purpose described.
3. In an ore roasting furnace having an outer, cylindrical wall a plurality of superposed roasting chambers and a rotary air-cooled rabble system, the combination of a metallic, downwardly extending conduit the external surface of said conduit being exposed to the atmosphere of certain of said roasting chambers and the lower end thereof being in communication with the lowermost of said chambers, means for conducting air from the upper end of the rabble system to the upper end of said conduit, and a conduit insulated from the heat of the furnace, for conducting air from the upper end of the rabble system to the lowermost of said chambers, substantially as and for the purpose described.

4. In an ore roasting furnace having an outer, cylindrical wall a plurality of superposed roasting chambers and a rotary air-cooled rabble system, the combination of a metallic, downwardly extending conduit the external surface of said conduit being exposed to the atmosphere of certain of said roasting chambers and the lower end thereof being in communication with the lowermost of said chambers, valved means for conducting air from the upper end of the rabble system to the upper end of said conduit, valved means for conducting air from the upper end of the rabble system into the atmosphere, and a valved conduit insulated from the heat of the furnace, for conducting air from the upper end of the rabble system to the lowermost of said chambers, substantially as and for the purpose described.

5. In an ore roasting furnace having an outer, cylindrical wall, a plurality of superposed roasting chambers and a rotary, air-cooled rabble system, the combination of a cylindrical system of metallic, vertically extending conduits within said cylindrical wall, a surface of each of said conduits being exposed to the atmosphere of certain of said roasting chambers and the lower ends of said conduits being in communication with one of said chambers, and means for conducting air from the upper end of the rabble system to the upper ends of said conduits, substantially as and for the purpose described.

In testimony whereof I have hereunto set my hand in the presence of two subscribing witnesses.

HARRY H. STOUT.
